UNITED STATES PATENT OFFICE.

GOTTLIEB C. HOFFMANN, OF WASHBURN, NORTH DAKOTA.

HUMIDIFIER.

Application filed January 13, 1927. Serial No. 160,954.

This invention relates to humidifying devices such as are used for humidifying the air in cigar display cases and under like situations and the general object of this invention is to provide a humidifier or moistener of this type which is very simple, which may be cheaply made, which may be run at small cost, and which has been found very effective in use.

10 A further object is to provide a humidifier of this character wherein a certain amount of water in a tank or container is heated by means of an electric bulb to a point where it will give off a small amount of vapor.

15 My invention is illustrated in the accompanying drawings wherein:—

Figure 1 is a vertical sectional view of a humidifier constructed in accordance with my invention;

20 Fig. 2 is a transverse section on the line 2—2 of Figure 1.

Referring to these drawings it will be seen that the humidifier consists of a tank 10 which may be made of copper, brass, or 25 any other suitable material. This tank 10 is designed to contain water up to the line indicated by the outwardly bulged corrugation 11 which extends around the four walls of the tank adjacent the top thereof. Ex- 30 tending across the top of the tank is a plate 12 which forms part of the tank and has an upstanding rim 13. This plate to one side of the circular opening bounded by the rim 13 is formed with a relatively small trans- 35 verse opening 14. Preferably the lower end of the tank adjacent one corner carries the angular partition 15 which defines a relatively deep water space 16 on one side of this partition and a relatively shallow water 40 space above the partition.

Extending over the circular opening formed in the plate 12 is a cap 17 which is 45 perforated at a plurality of points and carries the electric light socket 18. This cap has a depending flange 19 insertible into the rim 13, this flange being cut away or otherwise formed for engagement by set screws 20 on the rim 13. The electric light socket 18 carries the bulb 21 which is of such size 50 as to extend nearly to the bottom of the tank. The electric light socket is, of course, provided with the usual flexible cord conductors terminating in the usual plug or base whereby the bulb may be connected to a source of 55 electricity.

In the use of this device, the tank is filled

with water to about an inch from the top and the light is turned on. In about two or two and a half hours the water will become sufficiently heated so that a fine vapor will 60 arise from the tank which thoroughly moistens the air within the cigar display case. The electric light may be kept energized for any desired length of time or may be only used when the cigars become dry. 65 This cigar moistener is inexpensive compared with those now on the market and is particularly efficient. There are no parts to get out of order and it costs but little to run.

70 While I have designed this particularly for a humidifier to be used in cigar cases, I do not wish to be limited to this as it might be used for other purposes.

75 It will be particularly noted that the openings 17^a in the cap 17 are relatively large and there may be any desired number of these openings so as to permit free passage of the vapor out through these openings as the greatest amount of vapor will rise through this cover or cap because the water 80 around the bulb will be hottest. Thus, there will be no condensation of vapor immediately around the bulb which would be likely to trickle down the bulb.

85 The reason for making one-half of the tank or water-containing space shallower than the space immediately surrounding the bulb is that if the tank were of the full depth throughout its entire extent it would hold nearly twice as much water and thus 90 it would take twice as long to heat the water before the vapor would rise. This would render it more costly to operate. At the same time the water vaporizes quite rapidly and if the water tank merely surrounded 95 the bulb and was filled up to the neck of the bulb, it would require to be filled more often than convenient. The openings 17^a in the top 17 are to permit the vapor to pass directly up from the space surrounding the 100 hottest portion of the tank. The opening 14 is mainly used for filling, as if the opening 14 was not provided it would require to be filled through the openings 17^a, and if the bulb was hot at this time, the bulb would 105 crack. Furthermore, the vapor would not pass out as readily if the openings 17^a were omitted, these openings being at the highest portion of the tank.

I claim:—

110 A humidifier comprising a water tank formed to provide a relatively deep water

space and a connected shallow water space, the tank having a top provided with a vapor outlet opening above the shallow water space and an opening above the relatively 5 deep water space, said top being provided with a flange defining the last named opening, a cap adapted to be disposed over the last named opening and having a depending flange fitting into and detachably engaged 10 with the flange on the top of the tank, means extending through the flange on the top and engaging the flange on the cap for prevent-

ing accidental disengagement of the flanges, said cap having vapor outlet openings and having an inwardly turned screw-threaded 15 flange, an electric lamp socket having screw-threaded engagement with the flange, and an electric bulb carried by said socket and normally immersed in the water in the deep water space and having connections whereby 20 it may be energized.

In testimony whereof I hereunto affix my signature,

GOTTLIEB C. HOFFMANN.
